UNITED STATES PATENT OFFICE.

JAMES CHRISTY, OF CLEVELAND, OHIO.

DESIGN FOR A TIRE.

54,725.

Specification for Design. Patented Mar. 23, 1920.

Application filed November 24, 1919. Serial No. 340,430. Term of patent 14 years.

To all whom it may concern:

Be it known that I, JAMES CHRISTY, a citizen of the United States, residing at Cleveland, in the county of Cuyahoga and State of Ohio, have invented a new, original, and ornamental Design for Tires, of which the following is a specification, reference being had to the accompanying drawing, forming part thereof.

Figure 1 is a plan view, Fig. 2 is a perspective view of the tire tread as seen from one side, and Fig. 3 is a section of the tire on line 3—3, Fig. 1, showing my new design for a tire.

I claim:

An ornamental design for a tire, as shown.

JAMES CHRISTY.
